METALLIC ROOFING

John R. Boddie, 7522 S. Santa Fe, P.O. Box 60308,
Houston, Tex.

Filed Sept. 28, 1962, Ser. No. 226,851
6 Claims. (Cl. 50—200)

This is a continuation-in-part of U.S. patent application Serial No. 6,260, filed February 2, 1960, by John R. Boddie for "Metallic Roofing."

This invention relates to the art of roofing, and more particularly to roofing with interlocking metallic roof panels.

In the use of thin, interlocking sheet metal panels for roofing, considerable difficulty arises in making a watertight roof that is not subject to electrolytic decomposition, not subject to rattling by wind, and allows for simplicity of manufacture and assembly. Many attempts have been made in the past to provide metal-sheathed roofs having these qualities, but all have been found to be deficient in one or more of the above-recited qualities. Typical of the prior art are the roof constructions described in the following United States patents: No. 2,032,275, Fradette; No. 2,830,546, Rippe; No. 2,626,577, Roush et al.

According to one aspect of my invention, a metallic roofing panel is provided which is adapted for use with sheets of asphaltic felt (a resilient, pliable, waterproof roofing material) laid in overlapping layers on a substantially continuous inclined roof deck. The panel terminates at its lower edge in a re-entrant hook, and at its upper edge in an S-bend, or substantially S-shaped raised portion defining a notch or recess and a nailing flange extending beyond the upper edge of the notch. The hook and the raised upper portion are formed so that when the nailing flange is nailed to the underlying felt and roof deck, a layer of felt may be placed over the raised portion whereby the felt layer substantially fills the space between the raised upper portion and the next panel. In this manner, the portion of the felt subject to water drainage is not perforated by nails so that it is impossible for water to penetrate the felt. Weep holes may be provided in the re-entrant hook to facilitate water drainage out of the hook.

The objects and features of my invention will be more completely understood upon consideration of the following description thereof when taken in connection with the accompanying drawings, wherein:

FIGS. 1 and 2 are fragmentary cross-sectional views of a roof construction in accordance with my invention;

FIG. 3 is a fragmentary view of a portion of the construction of FIG. 1, illustrating the lock details of the structure;

FIG. 4 is an enlarged side view of one of the metallic panels of FIG. 1, more perspicuously illustrating certain constructional details thereof;

FIG. 5 is a top view of two shingles joined by a cleat in accordance with the invention;

FIG. 6 is an isometric view of ridge panels in accordance with the invention;

FIG. 7 is a top view of a metal blank from which the ridge panels are formed;

FIG. 8 is an enlarged fragmentary perspective view of a portion of the structure shown in FIG. 7; and

FIG. 9 is a perspective view of the cleat of FIG. 8 illustrated in its normal position.

The metallic roof panel 42 illustrated in FIGS. 1, 3, and 4 comprises a body portion 1 having a downwardly extending re-entrant hook at one end thereof and an upwardly extending portion defining a notch or recess at the other end thereof. The panel may be formed from any convenient sheet metal, preferably aluminum or copper, although

2

galvanized steel also is adapted for use with the invention. The panel may be between 2 and 8 feet in length and may be corrugated so that the distance between valleys or peaks is approximately 20 times the thickness of the sheet metal. If the panel is corrugated, the depth of the corrugations should be between 1 and 5 times the thickness of the sheet metal, depending on the temper of the sheet.

The re-entrant hook, which will be at the lower end 10 of the panel which it is laid as described below, comprises a downwardly extending portion 11 and a back-extending portion 12A. The normal angle between the body portion 1 and the downwardly extending portion 11 when the panel is not in position on a roof should be 15 slightly less than 90°, and preferably should be between 85° and 88°. The angle between the downwardly extending portion 11 and the back-extending portion 12A of the re-entrant hook should be approximately 80°, and preferably between 77° and 83°. Thus, angle α between a 20 plane parallel to body section 1 and back-extending section 12A will be approximately 15°, and preferably will be between 12° and 18°. One or more weep holes 12 are provided at the juncture of portions 11 and 12A.

The upwardly extending portion at the upper end of 25 the panel is formed by crimping the end of the panel back in an S-bend comprising a substantially 180° lower bend designated by the reference numeral 10, and then crimping it forward in a substantially 200° upper bend designated by the reference numeral 18. In this manner, 30 a notch or recess 38 is formed which is adapted to receive the back-extending portion of the re-entrant hook of a similarly constructed panel. The end of the panel at the upper end of the S-bend extends beyond the notch to form a nailing flange 39.

As can best be seen in FIG. 1, the metallic panel described above is meant to cover a substantially continuous roof deck 7 along with felt layers 28, 40, 40A, etc. The roof deck may be formed of boards, as shown, or of wood shingles where an existing roof is to be covered. The felts may be conventional resilient, pliable, waterproof sheets of rag or similar fibrous material, thoroughly saturated and coated with weathered asphalt. The felt functions to support the panels and provide the rigidity necessary to prevent rattling, to waterproof the assembly, and to act 45 as a sound deadener.

An eave or starter strip 32 is used to start the roof assembly. The eave strip 32 has a full return lip 33 to which the re-entrant hook of the first panel is hooked, 50 a drip edge 34 turned out slightly to hold water away from the building and to prevent capillary action from drawing water up between the eave strip and the building. The drip lip 35 serves to cover the edge of the roof deck to form a protective border around the roof edge and to flash water to the gutters. A fastening lip 36 extends over the edge of the roof to permit the eave strip to be nailed to the roof deck.

The felts and panels are applied starting at the eave, as can best be seen in FIG. 1. The first felt layer 28 is laid on the eave, the starter strip 32 is nailed thereover, 60 a felt layer 40 is nailed over the eave strip, and the re-entrant hook 29 of the first panel 42A is hooked over the return loop of the eave strip. The nailing flange 39 (see FIG. 4) is then nailed to the roof deck 7 through the felt. The flange 39 need not be driven against the felt; it has been found best to leave a small gap between the felt and the flange, particularly when wood shingles serve as the roof deck. Another layer of felt 40A is laid 65 so that the lower edge thereof extends over the nailing flange and the notch down to the 200° bend 18 in the sheet metal (see FIG. 1). The next panel 42B is applied by hooking the back-extending member into the notch. As illustrated in FIG. 3, the normal thickness of the felt

is at least as great, and preferably slightly greater than the space between the upwardly extending portion of the lower panel and the lower end 19 of the body portion 1 of the upper panel. When the re-entrant hook of the upper panel is hooked into the notch of the lower panel, the back-extending member 12A (see FIG. 4) contacts the lower panel at the points designated by the reference numerals 16 and 17. Thus, the portion of the lower panel at the 180° to 200° forward bend designated by the reference numeral 18 is forced down. Since the nailing flange 39 has been nailed, a very effective spring lock is formed. The lock holds the upper shingle securely in place against the felt and compresses the felt to prevent rattling of the panels. With reference to FIG. 1, the nailing flange of the upper panel is then nailed to the felt and the roof deck and the next and succeeding felt and panel members are applied in the same manner.

At the roof ridge (see FIG. 2), after the nailing flanges 39 of panels on both sides of the ridge have been nailed in place, a plurality of fibred ridge felt strips 30 are lapped over the ridge. Ridge shingles 31, which will be described in detail below with respect to FIGS. 6 and 7, are hooked in place and are nailed in place by nails 20. The ridge shingles 31 manifestly may be nailed through the topmost panels without affecting the waterproof quality of the roof. A nailing apron or ridge flange 15 (see FIG. 6) is nailed in place to secure the ridge panels to the roof.

FIGS. 6 and 7 illustrate the details of the Boston ridge shingles 31 in accordance with the teachings of the invention. At the lower edge 22 on each ridge is re-entrant hook similar in design to that described with respect to the panel member described in FIG. 2. Each re-entrant hook engages the recesses of the adjacent ridge member. A single lapped layer of felt lies over the ridge under the cover, as described above. Each cover section is formed from a sheet metal blank cut as shown in FIG. 7. The angle β of notch 26 is equal to the ridge angle of the roof covered. The blank also is cut on line 27 and is folded on lines 23 to form a re-entrant hook and notch similar to the hook and notch illustrated in FIG. 2. A nailing apron or ridge flange 15 secures the assembly at one end, and a re-entrant hook secures the assembly at the opposite end.

Abutting edges of each pair of adjacent panel members preferably are connected together as shown in FIGS. 5 and 8 by expansion cleat 50. As illustrated in FIGS. 8 and 9, each cleat is formed from one rectangular piece of sheet metal. The cleat comprises lower wings or flanges 53 and 61 extending upwardly and outwardly from a central web including portions 55 and 57. The top portion is bent backwardly upon itself to connect the web portions 55 and 57. The flanges 53, 61 normally extend above top portion 56, as is illustrated in FIG. 9. The length of the cleat is the distance from shingle portion 11 to the backbend 10 (see FIG. 4) measured along shingle body section 1.

When the roof is being assembled, abutting edges 63, 65 of adjacent flanges are forced between the lower flanges 53, 61 and the top member 56. The flanges bend down to grip the edges 63, 65 and hold them firmly in place. The felt sheet 67 underlays the cleat to provide complete waterproofing of the roof. The back-extending member 12A of the next upper shingles is slipped over cleat top portion 56 into the recess 38.

At chimneys and roof vents, flashings are set into the felts rather than into the metal panels. Therefore, all flashing materials are protected from the weather, and the life and effectiveness of the flashing materials is materially increased. The panels are also electrically insulated from the flashings and vent pipes, thus making it particularly feasible to use materials such as aluminum and copper, which are extremely resistant to oxidation but quite susceptible to electrolytic decomposition.

The invention allows for the use of standard steps,

flashing, and procedures common to the roofing industry. As the waterproofing is performed by the underlay rather than the metal surface and the ends of the metal are not cemented, locked or anchored, and the bottom locks move freely, the only anchor is the top, thus, expansion presents no problem. This provides an excellent recover roof over very rough surfaces, such as wood shingles. As the abrasion is covered by the felt and any reverse flow of water is thrown into a felt-to-felt gasket, flashing can be made into existing projection with roofing procedures, rather than sheet metal practice. All flashings can be made with felt and metal without the use of mastics, which deteriorate and cause leakage.

Foot traffic will not damage the roof. Should a person step on the lock or butt of a panel, the lock will be closed tighter. Water drainage is almost entirely over the panels. Water that does find its way under the panels (including condensation on the backside of the metallic sheath) will drain down over the felts into the re-entrant hook, through weep holes 12, and out over the panels to the ground. The nails that secure the nailing flanges to the roof deck are isolated from water contact so that it is not possible for water to penetrate the felt through the nail perforations.

A further advantage of the invention is that very thin metal can be used for the panels to minimize the cost of manufacture and installation.

From the above description, the importance of the angle between the downwardly extending and back-extending portions of the re-entrant hook can be readily appreciated. The angle must be small enough to hold tension on the panel yet large enough to permit interlocking between panels.

The invention is not necessarily to be restricted to the specific structural details or arrangement of parts herein set forth, as various modifications thereof may be effected without departing from the spirit and scope of the invention.

What is claimed is:

1. A roof structure for covering a substantially continuous roof deck, comprising:
a plurality of substantially rectangular sheets of resilient, pliable, waterproof roofing material on said roof deck partially overlapping each other at spaced intervals going up said roof deck, each upper sheet overlapping a portion of the immediately lower sheet; a plurality of sheet metal panels covering said sheets and interconnecting lower edges of said sheets, each of said panels having a body portion terminating in a downwardly extending re-entrant hook along the lower edge thereof and in a re-entrant notch portion along the upper edge thereof, each re-entrant hook engaging the re-entrant notch portion of the next lower panel, said re-entrant notch portion being formed as an S-bend with the upper end of the S-bend terminating in a nailing flange extending beyond the notch;

the topmost overlapping sheet covered by a given panel extending over the nailing flange of the panel immediately below said given panel and pressed between the upper end of the S-bend of said panel immediately below and the lower surface of the body portion of said given panel into the re-entrant hook of the given panel;

said nailing flange being nailed to the sheets thereunder and to the roof deck; the normal thickness of the sheets being at least the minimum distance between the body portion of one panel and the upper end of the S-bend of the next lower panel interconnected therewith whereby a given sheet is compressed between said body portion of one panel and said upper end of the S-bend of the next lower panel.

2. A roof structure as claimed in claim 1 wherein abutting, upwardly extending edges of adjacent panels are connected together by cleats comprising spaced apart verti-

cal webbed sections, an upper crosshead section connected to both of said vertical web sections and extending outwardly therefrom, and first and second flanges respectively connected to the lower ends of said first and second vertical web sections and extending upwardly and outwardly therefrom beyond and above the extremities of the crosshead section, each of said flanges fitting between the body portions of said adjacent panels and the resilient, pliable, waterproof roofing material thereunder, the length of said cleats being substantially the length of the body section of said adjacent panels.

3. In a roof structure for covering a substantially continuous roof deck, comprising:

a plurality of substantially rectangular sheets of resilient, pliable, waterproof roofing material on said roof deck partially overlapping each other at spaced intervals going up said roof deck, each upper sheet overlapping a portion of the immediately lower sheet; a plurality of sheet metal panels covering said sheets and interconnecting lower edges of said sheets, each of said sheet metal panels terminating in a re-entrant hook along one edge thereof and having a re-entrant notch portion along an opposite edge thereof; each said re-entrant hook engaging the re-entrant notch portion of the next lower panel, and comprising a downwardly extending portion forming an angle of substantially 85° with the body of the sheet metal panel, and an upwardly-extending portion at the lower edge of said downwardly extending portion, said upwardly-extending portion forming an angle of approximately 80° with said downwardly extending portion;

said re-entrant notch portion being formed as an S-bend with the upper end of the S-bend providing an outwardly-extending nailing flange along the top edge of the body portion;

said nailing flange being nailed to sheets of resilient, pliable, waterproof roofing material thereunder and to the roof deck;

the topmost overlapping sheet covered by a given panel extending over said nailing flange and said re-entrant notch portion of the panel immediately below said given panel and the nails therethrough, into the re-entrant hook of the given panel, and having a normal thickness which is at least the minimum initial distance between the body portion of said given panel and the upper leg of the S-bend of the next lower panel interconnected therewith, whereby said topmost overlapping sheet is compressed between said body portion of said given panel and the upper leg of the S-bend of said next lower panel.

4. A roof structure as claimed in claim 3 wherein abutting, upwardly extending edges of adjacent panels are connected together by cleats comprising spaced apart vertical webbed sections, an upper crosshead section connected to both of said vertical web sections and extending outwardly therefrom, and first and second flanges respectively connected to the lower ends of said first and second vertical web sections and extending upwardly and outwardly therefrom beyond and above the extremities of the crosshead section, each of said flanges fitting between the body portions of said adjacent panels and the waterproof roofing material thereunder, the length of said cleats being substantially the length of the body section of said adjacent panels.

5. A roof structure for covering a substantially continuous roof deck, comprising:

a plurality of substantially rectangular sheets of pliable, waterproof roofing material on said roof deck partially overlapping each other at spaced intervals going up said roof deck, each upper sheet overlapping a portion of the immediately lower sheet;

a plurality of sheet metal panels covering said sheets and interconnecting lower edges of said sheets, each of said panels having a body portion terminating in a downwardly extending re-entrant hook along the lower edge thereof and in a re-entrant notch portion along the upper edge thereof, said re-entrant hook engaging the re-entrant notch portion of a similarly constructed next lower panel, and comprising a downwardly extending portion forming an angle of substantially 85° with the body of the sheet metal member, and an upwardly-extending portion along the lower edge of said downwardly extending portion forming an angle of approximately 80° with said downwardly extending portion;

said re-entrant notch portion being formed as an S-bend with a short radius substantially 180° lower bend and a short radius substantially 200° upper bend, the upper bent section terminating in a nailing flange extending beyond the notch that receives the re-entrant hook of the next upper panel member, said nailing flange being nailed to the sheets thereunder and to the roof deck;

the distance between the body portion of one sheet metal panel and the upper leg of the S-bend of the next lower panel being less than the normal thickness of the pliable sheet of roofing material therebetween whereby said pliable sheet of roofing material therebetween is compressed between said body portion of said one sheet metal panel and said upper leg of the S-bend of the next lower panel.

6. A roof structure as set forth in claim 5 wherein abutting, upwardly extending edges of adjacent panels

40 are connected together by cleats comprising spaced apart vertical webbed sections, an upper crosshead section connected to both of said vertical web sections and extending outwardly therefrom, and first and second flanges respectively connected to the lower ends of said first and second vertical web sections and extending upwardly and outwardly therefrom beyond and above the extremities of the crosshead section, each of said flanges fitting between the body portions of said adjacent panels and the sheet of waterproof roofing material thereunder, the 45 length of said cleats being substantially the length of the body section of said adjacent panels.
